UNITED STATES PATENT OFFICE

PHILIP E. CARLSON AND CARL J. ULRICH, OF MINNEAPOLIS, MINNESOTA

LOCK

Application filed June 15, 1928. Serial No. 285,667.

Our invention relates to improvements in locks and more particularly to locks that are operated by electromagnetic means from a distant point. The improved lock, while intended for general use, is especially well adapted for use in connection with lockers whereby the circuits for operating a plurality of said locks may be connected in parallel and simultaneously operated. When the improved lock is used in connection with lockers in schools, shops or similar places these lockers may also have individual locks but said lockers will be simultaneously locked and unlocked at a given time by a master control in an office or the like to prevent said lockers from being opened except during specified times. The master control may be either manually operated or operated by a time clock.

To the above end, generally stated, the invention consists of the novel devices and combinations of devices hereinafter described and defined in the claims.

In the accompanying drawings, which illustrate the invention, like characters indicate like parts throughout the several views.

Referring to the drawings:

Fig. 1 is a view partly in elevation and partly in section showing the improved lock applied to a locker;

Fig. 2 is a view corresponding to Fig. 1 with the exception that the lock is released; and

Fig. 3 is a fragmentary view with some parts sectioned on the irregular line 3—3 of Fig. 1.

The numeral 4 indicates what may be assumed to be a steel locker and the numeral 5 indicates a swingable door therefor. Said locker 4, at its door opening, has an inturned flange that affords a door frame 6 and the door 5, at its marginal edge, has an inturned reinforcing flange 7.

The lock mechanism is mounted in a casing 8 rigidly secured to the inner face of the door 5 and which door forms a portion of said casing to completely close the same so that the lock mechanism cannot be tampered with. Said lock mechanism includes a horizontal lock bolt 9 rigidly secured at its

inner end to the lower end of a depending arm 10 pivoted to a bracket 11 in the casing 8 for vertical swinging movement parallel to the door 5. The lock bolt 9 is held by its arm 10 for projecting movement through aligned holes 12 and 13 in the door flange 7 and door frame 6, respectively, to lock the door closed, as shown in Fig. 1. A light flat spring 14 is anchored to the casing 8 and bears against the arm 10. This spring 14 with the assistance of gravity normally and yieldingly holds the arm 10 with the lock bolt 9 retracted, as shown in Fig. 2. The lock bolt 9 may be retracted either by a spring or by gravity or by both, as shown.

An actuator for successively and alternately causing the projecting and retracting movements of the lock bolt 9, is operated by electro-magnetic means, as will presently appear. This actuator, as shown, is in the form of a wheel 15 having in its periphery circumferentially spaced cams 16. Said wheel 15 has a shaft 17 journaled in the casing 8 and a bracket 18 secured to said casing. A roller-equipped stud 19 mounted on the arm 10 intermediate of its ends, is yieldingly held in contact with the periphery of the wheel 15 by gravity and the spring 14 to be acted on by the cam 16 to cause successive and alternate projecting and retracting movements of the lock bolt 9.

Steps of movement are imparted to the wheel 15 to successively and alternately cause the projecting and retracting movements of the lock bolt 9 by impulses produced by the electro-magnetic means heretofore referred to. This electro-magnetic means includes, within the casing, a pair of coils 20 and a co-operating armature 21 yieldingly and normally held retracted by a light flat spring 22. This spring 22 is attached to the armature 21 and engages a lug 23 as a base of resistance on the casing 8. For the purpose of this case it is not thought necessary to show the circuit for the coils 20 with the exception of the lead wires 24.

As previously stated, the switch for closing the circuit of the electro-magnetic means may be located in an office or other

distant point and may be manually operated or automatically controlled by a master clock.

Applied to the armature 21 is an angle-shaped extension 25, the free or upper end portion of which extends transversely over the shaft 17 at one side of the wheel 15. This armature extension 25 carries a pivoted spring-pressed pawl 26 that co-operates with a ratchet wheel 27 on the wheel 15 for imparting steps of movement to said wheel under the action of the armature 21. To prevent more than a predetermined movement of the wheel 15 by the pawl 26 so that the cams 16 are always properly positioned in respect to the roller-equipped studs 19, a stop finger 28 on the armature extension 25 is arranged to be successively projected in front of circumferentially spaced stop pins 29 on the wheel 15 during the rotation 20 of said wheel by a pawl 26 under the action of the armature 21 as the same is moved by the energized coils 20.

To releasably hold the wheel 15 where positioned by the pawl 26 at the completion 25 of the projecting movement of the lock bolt 19, depressions or seats 30 are formed in the cam 16 in which the roller-equipped stud 19 rests. The purpose of thus releasably holding the wheel 15 is to prevent the same from being accidentally removed.

What we claim is:

1. In a lock of the class described, a casing, a lock bolt mounted in the casing, a wheel having circumferentially spaced cams arranged to cause alternate projecting and retracting movements of the lock bolt, ratchet teeth on the wheel, electro-magnetic means including a pawl movable thereby and operative on the ratchet teeth for imparting steps of movement to the wheel for successively positioning the cams.

2. The structure defined in claim 1 in which the wheel is provided with circumferentially spaced stop surfaces, and in further combination with a stop member automatically positioned by the electro-magnetic means for co-operation with the stop surfaces to limit the steps of movement imparted to the wheel.

3. In a lock of the class described, a casing, a lock bolt having an arm pivoted to the casing and supporting the lock bolt for projecting and retracting movements, a wheel having circumferentially spaced cams, a cam member on the arm, said lock bolt being under strain to move into a retracted position and position its cam member to be engaged by the cams and cause alternate projecting and retracting movements of the lock bolt, and electro-magnetic means for imparting steps of movement to the wheel for successively positioning the cams.

4. In a lock of the class described, a casing, a lock bolt having an arm pivoted to

the casing and supporting the lock bolt for projecting and retracting movements a wheel having circumferentially spaced peripheral cams, said arm having a cam stud intermediate of its ends, said lock bolt and arm being under strain to move toward the wheel and yieldingly hold the cam stud on the periphery of the wheel to be acted on by the cams and cause alternate projecting and retracting movements of the lock bolt, and electro-magnetic means for imparting steps of movement to the wheel for successively positioning the cams.

In testimony whereof we affix our signatures.

PHILIP E. CARLSON. 80
CARL J. ULRICH.
